UNITED STATES PATENT OFFICE.

JAMES A. TAYLOR, OF WACO, KENTUCKY, ASSIGNOR OF ONE-THIRD TO NATHAN B. TURPIN, OF RICHMOND, KENTUCKY.

SPECTACLE-SUPPORT.

1,288,284.

Specification of Letters Patent. Patented Dec. 17, 1918.

Application filed May 24, 1918. Serial No. 236,403.

To all whom it may concern:

Be it known that I, JAMES A. TAYLOR, a citizen of the United States, residing at Waco, in the county of Madison and State 5 of Kentucky, have invented new and useful Improvements in Spectacle-Supports, of which the following is a specification.

This invention has reference to eye-glass or spectacle mounts.

10 The object of the invention is to provide means whereby the mount may be suspended entirely free from the face of the wearer, when the glasses are not required for immediate use, and also whereby the same may 15 be readily swung to proper position when desired for use.

A further object of the invention is to produce a supporting means for eye-glass lens whereby the same may be retained 20 either over or away from the eyes of the user, and when brought to operative position will not frictionally engage with or inflict injury to the nose of the wearer.

Other objects and advantages will appear 25 as the nature of the invention is better understood, reference being had to the accompanying drawings, in which,

Figure 1 is an end elevation of the improvement showing the same attached to the 30 vizor of a cap.

Fig. 2 is a bottom plan view showing the lens folded against and latched on the vizor.

Fig. 3 is a section on the line 3—3 of Fig. 2.

35 Fig. 4 is a sectional view on the line 4—4 of Fig. 2.

Fig. 5 is a sectional view approximately on the line 5—5 of Fig. 2.

Fig. 6 is a detail longitudinal sectional 40 view through one of the sockets illustrating a modification.

In the drawings my improvement is illustrated as applied to the vizor of a cap, but it is to be understood that the same may be 45 attached to the brim of a hat, if desired. In either instance the improvement serves as a reinforcement for the vizor or brim, as will be apparent as the description proceeds.

The cap is indicated by the numeral 7, 50 and the vizor thereof by the numeral 8.

To the under side of the vizor, centrally thereof I secure a headed member in the na-

ture of a lug 9. The lug has its inner end provided with a flat head 10 from which extends a threaded stem 11 that passes 55 through a suitable opening in the vizor, and the said stem is engaged by a cap nut 12, which clamps the lug to the vizor.

On the vizor, inward of the stud 9, and disposed at points arranged an equal distance from the opposite sides of the stud 9 I arrange headed members 13. These headed members are centrally slotted from the outer sides thereof, and the said heads are provided with threaded stems 14 that pass 65 through suitable openings in the vizor 8. The stems are engaged by cap nuts 15 on the outer face of the vizor, and between the heads and the vizor the stems are surrounded by washers 16.

In the notched heads 13 are arranged the flat round ends 17 of interiorly threaded sockets 18, a pivot 19 passing through the heads and connecting the sockets to the respective heads. The sockets 18 are free to 75 swing in one direction, but the same are disposed in the path of contact with the inner walls provided by the notches in the heads 13 so that an inward movement of the said sockets is thus limited. The pivot members 19 are preferably in the nature of headed threaded elements designed to compress the notched head against the elements 17 of the sockets 18, and consequently regulate the frictional engagement of the said 80 elements with the opposing walls provided by the sockets of the head. This permits of the sockets being arranged at a desired angle with respect to the heads and held at such an angle.

As disclosed in Fig. 6 of the drawings the socket 18' has one of its ends provided with a ball head 20 that is received in a socket 21 on an element 17' that is pivoted to and frictionally contacted by the opposing walls 95 in the slot of a headed member 18', similar to the member 18. By this arrangement it will be noted that the socket 18' may be rotated, and the purpose of this arrangement will presently be apparent.

An eye-glass mount is indicated by the numeral 21, the same carrying the usual lenses 22 and being connected by a bridge piece 23. The bridge piece is of bendable ma-

terial so that the lenses 22 will be adjustable toward or away from each other. The elliptical portions of the mount, which receive the lens 22, are each provided with a centrally arranged threaded stem 24, and the said stems are adjustably received in the respective threaded sockets 18 or 18'.

When the device is not in use the bridge piece 23 frictionally engages between the 10 head and stem of the stud 9, thus holding the eye-glass against the vizor, as illustrated in Figs. 2, 3 and 4 of the drawings. The bridge piece 23, embodies a natural resiliency so that when a proper adjustment is 15 made between the stems 24 and the sockets 18 or 18' a firm engagement between the bridge piece and the stud is insured.

Under ordinary conditions only one longitudinal adjustment of the threaded stems 24 20 with respect to the sockets 18 or 18' is necessitated, and to accomplish this the nuts 15 are removed from the stems 14 of the head members 13, permitting a turning of the said heads with the sockets 18, thus bringing 25 the lens mount toward or away from the sockets. When a proper adjustment is obtained the cap nuts 15 are again positioned upon the stems of the heads 13. However, if desired, the device may be constructed as 30 illustrated in Fig. 6 of the drawings, in which event the cap nuts for the head members are not interfered with, but the sockets 18' are turned around the head members causing the stems 24 of the eye-glass mount 35 to be moved inward or outward of the sockets.

Having thus described the invention, what I claim is:

1. In combination with the beak or brim of a cap or hat, a stud thereon, headed members secured to the beak or brim to the opposite sides of and to the rear of the stud, an eye glass mount, longitudinally adjustable members associated therewith pivotally connected to the said headed members, and said 40 mount designed to frictionally engage with the stud when swung upon the beak or brim against said stud.

2. In combination with the beak or brim of a cap or hat having oppositely spaced 50 openings therein and an intermediate opening arranged centrally and forwardly of said spaced pair of openings, a stud having a headed portion and a threaded stem extended from such head, said stem extending 55 through the central opening, a cap nut screwed on said stem, headed members having threaded stems adapted to be passed through the remaining openings, a washer on each of said stems, a cap nut engaging 60 said stems, sockets pivotally secured to said heads, means between said sockets and heads for limiting the swinging of the latter in one direction, means for holding said sockets at an angle with respect to said heads, an 65 eye-glass mount adjustably connected with the sockets, and said mount adapted to frictionally engage with the stud, when the said mount is swung to one position, to hold the mount in such position.

In testimony whereof I affix my signature.
JAMES A. TAYLOR.
